UNITED STATES PATENT OFFICE.

NAMAKA L. FAUFATA, OF PAIA, TERRITORY OF HAWAII.

RAILROAD APPLIANCE.

1,145,473.

Specification of Letters Patent.

Patented July 6, 1915.

Application filed September 4, 1914. Serial No. 860,306.

To all whom it may concern:

Be it known that I, NAMAKA L. FAUFATA, a citizen of the United States, residing at Paia, in the county of Maui and Territory 5 of Hawaii, have invented certain new and useful Improvements in Railroad Appliances, of which the following is a specification, reference being had to the accompanying drawings.

10 This invention relates to certain improvements in railroad appliances and has relation more particularly to devices of this general character under electrical control; and an object of the invention is to provide a 15 device of this general character having novel and improved means whereby a train may be brought automatically to a standstill should the same pass beyond a danger signal.

The invention also has for an object to provide 20 a novel appliance of this general character wherein the operating circuits therefor are under control of a semaphore or the like and whereby said operating circuits can be closed only when the semaphore or the like 25 is at a predetermined adjustment.

It is also a further object to provide an 30 appliance of this general character having novel and improved means whereby the operation of the brakes of a train may be automatically set upon the train passing beyond a given point and whereby such means may 35 be substantially automatically reset upon the release of the brake.

The invention consists in the details of 40 construction and in the combination and arrangement of the several parts of my improved railroad appliance whereby certain important advantages are attained and the device is rendered simpler, less expensive and otherwise more convenient and advantageous for use, all as will be hereinafter 45 more fully set forth.

The novel features of the invention will be carefully defined in the appended claim.

45 In order that my invention may be the better understood, I will now proceed to describe the same with reference to the accompanying drawings, wherein—

Figure 1 is a diagrammatic view of an ap-

pliance constructed in accordance with an 50 embodiment of my invention; Fig. 2 is an elevational view, illustrating the means herein embodied for operating the brake controlling means; Fig. 3 is a view in elevation of the mechanism herein embodied for controlling the brake mechanism. 55

As disclosed in the accompanying drawings, 2 denotes a rail of a track structure, and 3 a semaphore disclosed in the accompanying drawings as adjusted into a position indicative of danger. The operation of this semaphore forms no part of my present invention and for this reason it is thought that a detailed description thereof is unnecessary, other than to state that it is under 60 control of the semaphore rod 4 disposed upwardly within the standard 5 and has affixed thereto the contact 7 adapted to be in engagement with the stationary contact 9, supported by the standard 5 when the semaphore is in its position hereinbefore mentioned. 70

The contacts 7 and 9 are electrically connected, as herein disclosed, through the medium of the conductor *h* and *i*, respectively, 75 with the brush 10 and the rail 2; the brush 10' being positioned in close proximity to said rail 2 of the track-way. The brush 10' is adapted to be engaged by the shoe 11 carried by the locomotive *L* and of a construction and arrangement substantially identical as the shoe 11, hereinbefore referred to, and said shoe is electrically connected through the medium of the conductor *j* with the electromagnet *E'* mounted upon the base 72, 85 said base in actual practice being preferably positioned within the cab of the locomotive. The electromagnet *E'* is also electrically connected with the rail 2 through the medium of the conductor *k* in a conventional manner, and, as herein embodied, the conductor *k* has interposed therein the source *S³* of electrical energy. By this arrangement, it will be seen that with the semaphore 3 in a position indicative of danger and the shoe 11' in contact with the brush 10', the circuit thus closed will impart movement to the armature *A²*, said armature being herein dis-

closed as pivotally supported by the up-standing arm 73 carried by the base 72 and provided with the rock arm 74 which is operatively connected, as at 75, with the latch bar 76, the free extremity whereof being adapted to coact with the latch 77 carried by the vertically movable member 78 to normally hold such member 78 in an elevated position. As herein disclosed, the member 78 is slidably supported within the guide 79 carried by a standard 80 projecting upwardly from the base 72, and said upright 80 is also provided with the upstanding arm 81 provided with a suitable opening 82 through which projects the bar 76 whereby said lever is maintained in proper position.

The lower extremity of the arm 78 is operatively engaged with the movable contact 83, and upon release of the member 78 such contact 83 is caused to engage the stationary contact 84, and said contacts 83 and 84 are electrically connected through the medium of the conductors *l* and *m*, respectively, with the winding or coil *W*, and the conductor *m* has interposed therein the source *S*⁴ of electrical energy, and when the winding or coil circuit is closed, the core or solenoid 85 is caused to engage the pivoted latch member 86, carried by the handle 96, and disengage the same from the handle lever 87, herein disclosed as pivotally engaged intermediate its length with the standard 88 projecting upwardly from the base 89, on which base the standard 90 of the coil or winding *W* is also secured. The outer extremity of the handle lever 87 has operatively engaged therewith through the medium of the adjustable hook member 91, one extremity of the retractable member 92 herein shown as a coil spring, the opposite or lower extremity of such member 92 being connected with the hook member 93 projecting upwardly from the base 90. The member 92 possesses such tension as to rock the lever 87 when released and cause the same to engage the upper extremity of the stem 94 of the check valve 95, whereby air is caused to discharge from the main line of the brake system and the brakes caused to be set. As the particular construction of the brake system forms no part of my invention, a detailed description or disclosure thereof is believed to be unnecessary.

The handle 96 is pivotally engaged with the standard 88 and is normally maintained in a horizontal position through the medium of the spring latch 97 operatively supported by the standard 98, and in order to release the brakes, the latch 97 is disengaged through the medium of the push rod 99 and the handle 96 moved upwardly until the latch 97 engages the lever 87 and whereupon the handle 96 is returned to its normal posi-

tion with a result which is believed to be clearly obvious to those skilled in the art to which my present invention appertains.

The handle 96 is electrically connected through the standard 88 and the conductor *n* with the stationary contact 100 with which is adapted to coact the movable contact 101 also carried by the member 78. The movable contact 101 is electrically connected with the electromagnet *E*³ through the medium of the conductor *o*, and said magnet *E*³ is also electrically connected through the medium of the conductors *p*, *q* with the contact 102 adapted to be engaged by the contact 103 depending from the handle 96, and the contact thus closed results in movement of the armature *A*² herein disclosed as pivotally supported intermediate its length by the standard 104 projecting upwardly from the base 72 and having its rear end provided with an up-standing projection 105 adapted to engage the projection 106 carried by the member 78 whereby said member is elevated to disengage the contacts 83, 84, 100 and 101, the upward movement imparted to the member 78 being sufficient to cause the latch 77 of the member 78 to be operatively engaged by the bar 76, as is believed to be clearly apparent to those skilled in the art to which my present invention appertains. I also find it of advantage to have the contact 103 provided with the peripheral insulation 107 so that normally the circuit for the electromagnet *E*³ is broken. Interposed in the conductor *n* is the source *S*² of electrical energy.

From the foregoing description, it is thought to be obvious that a railroad appliance constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

In combination with an air brake system including a main line having a valve interposed therein, a lever supported for rocking movement, a handle lever, means for locking said handle lever and the first named lever one to the other whereby the same may be caused to move in unison and in the same general direction, means for imparting independent movement to the first named lever when the locking means is released whereby

said first named lever may engage and force the valve into open adjustment, electrically controlled means for releasing the locking means, said electric means including a circuit closer, separate electrically controlled means for operating the circuit closer, and an additional electrically controlled means for returning the second named electrically controlled means to normal position, said

last named electric means including a circuit closer wherein one of the contacts is carried by the handle lever.

In testimony whereof I hereunto affix my signature in the presence of two witnesses.

NAMAKA L. FAUFATA.
